TOBACCO HANGER

Wiley Z. Barkley, Elm City, N. C.

Application April 8, 1954, Serial No. 421,892

1 Claim. (Cl. 214—16)

This invention relates to a tobacco hanger, and more particularly to a device for facilitating the hanging of tobacco sticks on and the removal of the same from the tiers of tier poles while standing on the floor of a barn.

An object of this invention is to provide a tobacco hanger consisting of a plurality of tier poles which are mounted for vertical movement within a barn.

Another object of this invention is to provide a tobacco hanger having novel means for raising and lowering the tier poles within a tobacco barn.

A further object of this invention is to provide a tobacco hanger having novel guide means for guiding the tier poles in vertical movement within a tobacco barn.

A yet further object of this invention is to provide a tobacco hanger having the above characteristics which can be simply and efficiently installed in existing barns and which is durable and lasting in use.

These, together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a longitudinal vertical sectional view of a tobacco barn showing the tobacco hanger mounted therein;

Figure 2 is a transverse vertical sectional view of the barn showing the improved tobacco hanger mounted therein;

Figure 3 is a sectional view taken substantially along the section line 3—3 of Figure 2;

Figure 4 is an enlarged perspective view of the clevis for supporting the uppermost tier pole of each set; and

Figure 5 is an enlarged perspective view of the bracket for supporting the lower tier poles of each set.

Referring now more particularly to the accompanying drawings there is disclosed a tobacco curing barn having front and rear end walls 10 and 12, respectively. The front and rear end walls are substantially sealed and the front wall 10 is provided with a conventional door 14. The barn is further provided with side walls 16. The side walls 16 are formed of a plurality of spaced parallel boards which allow the passage of air therethrough for ventilation of the barn. A plurality of pairs of vertically extending studs 18 are provided for supporting the boards of the side walls 16. The purpose of the provision of pairs of studs 18 will be later described.

A plurality of tier poles 20 are disposed within the barn and have their opposite ends received between the pairs of vertical studs 18. The tier poles 20 are arranged in sets so that a plurality of tier poles rests between aligned pairs of vertical studs 18. The sets of tier poles 20 are horizontally spaced from each other and extend the full length of the barn.

Means are provided for connecting the tier poles 20 of each set together. This means comprises a chain 22

2

which is folded in half and has the free ends thereof adjacent each other. A clevis having a web portion 24 and a pair of depending legs 26 is secured to the chain adjacent the fold therein and with the chain entrained around the web portion 24. The free ends of the leg portions 26 of the clevis are provided with inwardly extending flanges 28. The tier poles 20 are adapted to be positioned between the leg portions 26 and resting on the flanges 28. The leg portions 26 are each provided with an aperture 30 adjacent their free ends. The apertures 30 in the legs 26 are in alignment with each other and the tier poles 20 are provided with an aperture 32 extending therethrough which is adapted to be placed in alignment with the apertures 30. Suitable fasteners 34 extend through the links of the chain and through the aligned apertures 30 and 32 for securing the clevis and tier pole 20 in position on the chain.

The lower tier poles of each set are secured to the chain 22 by means of suitable brackets. These brackets are formed of a pair of spaced parallel plates 36. The plates 36 are provided at one end with inwardly extending flanges 38. The plates 36 are further provided with apertures 40 extending therethrough and in alignment with each other adjacent the flanges 38. The fasteners 34 are adapted to pass through the links of the chain 22 and through the aligned apertures 40 in the plates 36 and apertures 32 in the tier poles 20 for securing the lower tier poles to the chain 22.

Rotatably mounted within the barn adjacent the top thereof are a pair of spaced parallel shafts 42. Suitable bearing blocks 44 may be utilized for mounting the shafts 42 in position. Fixedly secured to each of the shafts 42 are a plurality of pulleys 46 which are spaced longitudinally along the shaft 42. One of the pulleys 46 is positioned in overlying relationship to each set of tier poles 20. A flexible cable 48 is secured at one end in any suitable manner to the web portion 24 of the clevis. The other end of the flexible member 48 is secured in any suitable manner to the pulleys 46. Thus, it will be seen that rotation of the shafts 42 will cause the cables 48 to be either wound or unwound on the pulleys 46 thereby raising and lowering the tier poles 20 within the barn.

A suitable source of power 50, such as an electric motor or the like, is mounted in any convenient position adjacent the top of the barn. A double sprocket 52 is secured to the drive shaft of the motor and a single sprocket 54 is fixedly secured to one end of each of the shafts 42. A suitable chain 56 is entrained around the sprockets 52 and 54 whereby the motor 50 can drive the shafts 42.

The barn is provided with a conventional roof structure 58 for covering the same.

While the power means has been disclosed in the drawings as being placed within the barn, the same could be placed outside of the barn and the shafts 42 could be provided with extensions extending outside of the barn for connection to the power means. Further, the belt and pulley arrangement shown could be replaced by a chain and sprocket arrangement.

In practical use of the device, when it is desired to suspend sticks of tobacco within the barn, the power means is operated to lower the sets of tier poles into the bottom portion of the barn. Then, the sticks of tobacco can be placed in position extending between the tier poles of the adjacent sets. As the upper tier poles are loaded, the power means may be actuated to raise the sets a desired amount whereby sticks of tobacco may be placed on the next lower tier poles. This operation is continued until all of the tier poles have been loaded and the sets of tier poles are raised to the upper portion

of the barn where they will remain until the tobacco is cured. The reverse operation takes place when it is desired to unload the tier poles.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claim.

What is claimed as new is as follows:

A tobacco hanger for use in a tobacco curing barn, said hanger comprising a plurality of tier poles, said tier poles being arranged in horizontally spaced sets with the poles in each set being in vertically spaced relation in the same vertical plane, a plurality of pairs of flexible members, each pair of flexible members connecting the opposite ends of the tier poles of a set together, a pair of spaced parallel shafts adapted to be rotatably mounted adjacent the top of a barn in overlying relationship to the opposite ends of the tier poles, means mounted on said shafts for connecting one flexible member of each pair to one of said shafts and the other flexible member of each pair to the other of said shafts, and drive means for imparting rotation to said shafts to simultaneously lower said sets of tier poles to a compacted position in

the lower portion of the barn and to simultaneously elevate them to vertically spaced positions in the upper portion of the barn, and a plurality of pairs of vertical guideways adapted to be mounted in the barn, each pair of guideways receiving the ends of the tier poles of each set and guiding the same for vertical movement, each of said flexible members comprising an elongated chain having the free ends thereof disposed adjacent each other and with the intermediate portions thereof disposed in spaced parallel relationship, a plurality of brackets secured to said intermediate portions in vertical spaced relation, said brackets including pairs of spaced L-shaped plates engaging and supporting the ends of the tier poles, the upper bracket of said brackets being in the form of a clevis, said chain being entrained around the web portion of said clevis, said means connecting said flexible members to the shafts including a cable secured at one end to the web portion of the clevis, said cable being secured at its other end to said shaft.
